UNITED STATES PATENT OFFICE.

EDMUND S. SPINNEY, OF ABINGTON, MASSACHUSETTS, ASSIGNOR TO WHITMAN
PATCHING MACHINE COMPANY, INCORPORATED, OF WHITMAN, MASSACHUSETTS,
A CORPORATION OF MASSACHUSETTS.

TAG-PATCHING MACHINE.

Application filed August 13, 1925. Serial No. 50,041.

To all whom it may concern:

Be it known that I, EDMUND S. SPINNEY, citizen of the United States, residing at Abington, in the county of Plymouth and 5 State of Massachusetts, have invented new and useful Improvements in Tag-Patching Machines, of which the following is a specification.

This invention relates to a machine organized to simultaneously cut two circular reinforcing patches from gummed strips of paper or other suitable material; press the patches against opposite sides of a tag and perforate the tag and the patches to form a 10 string-receiving hole therein. The patches are cut by male and female cutting dies acting within guides having slots through which the gummed strips pass in the path of the male dies. The guides and dies 15 become coated with adhesive rubbed from the strips, and require frequent removal from the machine in order that they may be cleaned.

One object of the invention is to enable 25 the guides and the dies cooperating therewith to be removed from the frame and other parts of the machine, to be cleaned, and then replaced quickly and conveniently without employing a skilled machinist and 30 with a minimum expenditure of time.

Another object is to so improve the mechanism for operating the movable dies as to cause a more effective pressure of the patches against the tag than heretofore.

35 I attain the above mentioned and other incidental objects by the improved construction hereinafter described and claimed.

Of the accompanying drawings forming a part of this specification,—

40 Figure 1 is an end view of a machine embodying my improvements, the usual means for moistening the gummed strips and feeding them to and from the machine, being omitted.

45 Figure 2 is a side elevation of the machine as shown by Figure 1.

Figure 3 is a section on line 3—3 of Figure 2 looking downward.

50 Figure 4 shows in perspective one of the eccentrics hereinafter described, and its cam-shaped projections, and its eccentric wrist pin removed from the eccentric.

Figure 5 shows in perspective one of the male punch-cutting dies and its head.

Figure 6 shows in perspective one of the 55 guides and the hereinafter described tension rod and its clamping nut.

Figure 7 is a section on line 7—7 of Figure 2.

Figures 8 and 9 are views similar to Figure 6, showing different stages of the operation.

Figure 10 shows an ordinary shipping tag.

The same reference characters indicate the 65 same parts in all of the figures.

The frame of the machine is designated as a whole by 12 and may be of any suitable form. The frame is preferably vertically elongated and provided with upper and lower bearings 13 for the driven shafts constituting elements of the mechanism for operating the movable dies. The frame is provided between said bearings with a shelf 70 or table 14 on which a tag is moved by hand 75 to position to receive the reinforcing patches.

15, 15 designate the aligned tubular guides in which the movable dies (hereinafter described) are reciprocated. The guides are fixed to the frame with their bores in alignment with each other, their adjacent ends being sufficiently spaced apart to permit the insertion of a tag between them. The guides are provided with slots 16 arranged to guide 80 gummed strips 17 across the bores of the 85 guides.

In accordance with my invention, I provide the frame with recessed positioning abutments 18 for the guides 15, and associate with the frame and the guides, clamping means adapted to releasably confine the guides against the abutments and permit the removal of the guides from the frame, the form of the external surfaces of the guides and the form and arrangement of the recessed abutments being such that when the guides are in operative contact with the abutments, their bores are in exact alignment with each other. In this instance, each abutment 18 has two oblique faces 18^a forming the sides of an approximately V-shaped recess, and the guides have cylindrical peripheries concentric with their bores. I prefer to embody the clamping means in tension rods 20 fixed to the guides and 90 removably inserted in orifices extending through the frame, the rods being threaded at their outer ends and provided with 100

clamping nuts 21. When the nuts are turned inward against a face of the frame 12, the guides 15 are clamped against and positioned by the abutments 18, and when the nuts are removed, the guides and their tension rods are removable from the frame.

The machine includes the usual male and female patch-cutting dies 22 and 23 (Figures 7, 8 and 9) adapted to cut patches *p* (Figure 10) from the gummed strips 17, and the usual male and female perforating dies adapted to form holes *h* in the patches and in a tag against the opposite sides of which the patches have been pressed. The female patch-cutting dies 23 are fixed in the guides 15. The male patch-cutting dies 22 are guided by and reciprocated in the guides 15, said dies having elongated shanks 22^a having a sliding fit in the bores of the guides. The perforating dies include a single male die 24 movable in the bore of the upper punch-cutting die 22, and provided with a shank 24^a projecting from the shank 22^a, and a single female die 25 formed by the intersection of the bore and the acting end of the lower male patch-cutting die 22. When the dies 22 are retracted as shown by Figure 7, the gummed strips 17 are movable in the guides by usual feeding mechanism (not shown) organized to hold the strips at rest when the cutting and perforating dies are acting. When the dies 22 are projected, two patches are cut and pressed against the sides of the tag as shown by Figure 8, the male perforating die 24 remaining in a retracted position. While the male dies 22 are projected, the male perforating die 24 is projected as shown by Figure 9, and forms the hole *h*, the blanks cut from the patches and tag passing downward through the bore of the lower male die 22.

The male perforating die 24 is pressed upward by a spring 28 against the upper one of two operating eccentrics 29 fixed to upper and lower driven shafts 30 journaled in the bearings 13. The shafts may be driven by a motor (not shown) connected with one of the shafts and by a sprocket chain 31 engaged with sprocket wheels 32 fixed to the shafts. The eccentrics 29 are provided with elongated cam-shaped projections 32 extending from end to end of the eccentrics and arranged to bear on spaced apart trundle rolls 33 (Figure 5) mounted loosely on ears 34 formed on heads 35 fixed to the shanks 22^a of the male punch-cutting dies. The eccentrics 29 are provided with wrist pins 36 eccentric to the shafts 30 and connected by links 37 with studs 38 fixed to ears 34 of the heads 35. The movement of the eccentrics from the position shown by Figure 7 to that shown by Figures 8 and 9, causes the eccentrics to project the male punch-cutting dies.

The function of the links is to retract the

male patch-cutting dies when the eccentrics are moving from the position shown by Figure 9 to that shown by Figure 7. To permit the projection of the dies 22 by the cam-shaped projections 32 without causing the links 37 to bind on the wrist-pins 36 and studs 38, the links are provided with elongated slots 37^a, shown by dotted lines in Figure 4, the slots receiving the studs 38 so that the links have a limited endwise movement on the studs.

The upper eccentric 29 (shown by Figure 4) is provided with a central cam-shaped projection 40 diametrically opposite the projection 32 of that eccentric and arranged to pass between the trundle rolls 33 on the upper head 35. The shank 24^a of the male perforating die 24 projects between the trundle rolls into the path of the cam-shaped projection 40, the arrangement being such that the projection 40 projects the male perforating die as shown by Figure 9. The shank 24^a is preferably provided with an anti-friction ball 41 contacting with the upper eccentric and its cam-shaped projection 40.

The links 37 are slidable on the wrist-pins to the right from the positions shown by Figure 2, and are confined on the studs 38 by split collars 42, secured to the studs by clamping screws 43.

It will now be seen that to permit the removal of the guides 15 and the various dies from the machine, it is necessary only to remove the clamping nuts 21, these being removable by an attendant, who is not necessarily a machinist. When the nuts are removed, the guides, the dies, and the links 37 may be freely moved to the right from the positions shown by Figure 2.

It will also be seen by reference to Figures 7, 8 and 9, that the male patch-cutting dies are held projected and press the patches against the tag while the eccentrics are moving from the positions shown by Figure 8, to and beyond the position shown by Figure 9, the cam-shaped projection 40 acting through the shank 24^a and the spring 28 to hold the upper male die projected while said projection 40 is moving across the shank 24^a, so that a prolonged pressure of the patches against the tag is caused by the portions of the eccentrics between the points *x* and *y* (Figure 8).

I claim:

1. A tag patching machine comprising a frame, aligned tubular guides fixed to the frame and adapted to guide gummed patch strips, male and female patch-cutting dies adapted to cut patches from said strips and press the patches against opposite sides of a tag inserted between the guides, the female cutting dies being fixed in the guides and the male dies movable therein, a male perforating die movable in one of the male

cutting dies and adapted to perforate the tag and the patches, and operating mechanism for reciprocating the male cutting and perforating dies, the machine being characterized by fixed recessed positioning abutments on the frame, and clamping means associated with the frame and the guides and adapted to releasably confine the guides against the abutments and permit the removal of the guides from the frame, the arrangement being such that the abutments align the guides when the latter are confined.

2. A tag patching machine comprising a frame, aligned tubular guides fixed to the frame and adapted to guide gummed patch strips, male and female patch-cutting dies adapted to cut patches from said strips and press the patches against opposite sides of a tag inserted between the guides, the female cutting dies being fixed in the guides and the male dies movable therein, a male perforating die movable in one of the male cutting dies and adapted to perforate the tag and the patches, and operating mechanism for reciprocating the male cutting and perforating dies, the machine being characterized by fixed recessed positioning abutments on the frame, and tension rods fixed to the guides, extending through orifices in the frame, and provided with clamping nuts adapted to be set up against a face of the frame to position the guides, and removed to permit the removal of the guides and tension rods from the frame, the arrangement being such that the abutments align the guides when the latter are confined.

3. A tag-patching machine comprising a frame, aligned tubular guides fixed to the frame and adapted to guide gummed patch strips, male and female patch-cutting dies adapted to cut patches from said strips and press the patches against opposite sides of a tag inserted between the guides, the female cutting dies being fixed in the guides and the male dies movable therein, a male perforating die movable in one of the male cutting dies and adapted to perforate the tag and the patches, and operating mechanism for reciprocating the male cutting and perforating dies, the male cutting dies being

provided with heads having trundle rolls and outwardly projecting studs, the mechanism for reciprocating the movable dies comprising driven shafts journaled in bearings on the frame, eccentrics fixed to said shafts and provided with cam-shaped projections, eccentric wrist-pins secured to the eccentrics, heads fixed to the movable patch-cutting dies and provided with trundle rolls and studs, links connecting the wrist-pins with the studs to retract the movable patch-cutting dies, the links being slidable on and removable from the wrist-pins, and means confining the links on the studs.

4. A tag-patching machine comprising a frame, aligned tubular guides fixed to the frame and adapted to guide gummed patch strips, male and female upper and lower patch-cutting dies adapted to cut patches from said strips and press the patches against opposite sides of a tag inserted between the guides, the female dies being fixed in the guides and the male dies movable therein, a male perforating die movable in the upper male cutting die and provided with a projecting shank, upper and lower heads fixed to the male cutting dies and provided with spaced apart trundle rolls, upper and lower driven shafts journaled in bearings on the frame, upper and lower eccentrics fixed to the shafts and contacting with the trundle rolls, elongated cam-shaped projections on the peripheries of the eccentrics also contacting with the trundle rolls to project the male cutting dies, an inner cam-shaped projection on the upper eccentric arranged to pass between the trundle rolls on the head of the upper patch-cutting die and project the male perforating die, and a spring pressing the shank of the male perforating die against the portion of the upper eccentric having the inner cam-shaped projection, the arrangement being such that the eccentrics, their cam-shaped projections, and the spring supporting the male perforating die, cause a prolonged pressure of the patches against the tag.

In testimony whereof I have affixed my signature.

EDMUND S. SPINNEY.
